Attorney

UNITED STATES PATENT OFFICE.

KÄRL FAHLAND, OF DESSAU-GROSSKUHNNAU, GERMANY.

DRUM-MILL FEEDER.

Application filed July 15, 1927, Serial No. 206,105, and in Germany February 18, 1927.

My invention relates to drum mills of all types. In such mills the fitting together of the stationary inlet hopper and the rotating drum of the mill offers great difficulties. It 5 has been proposed to provide the inlet hopper for feeding the material into the mill with a hub projecting into the hub of the drum. In this way it was however impossible to obtain the necessary tight fit between both parts. 10 For this reason it was up to now necessary to place so-called flour collectors below the gap between the inlet-hopper and the mill-collar in order to catch the material dropping out. 15 My invention eliminates these disadvantages entirely. I attain this result by providing in the stationary feeding hopper for introducing fresh material into the revolving drum a special guiding chute of iron which 20 at its lower end projects far into the hub of the mill drum and may be replaced very easily. The great advantages brought about by such a sheet iron lining or guiding chute is obvious. 25 With such a device it is possible to introduce substantially the entire quantity of material into the rotating mill, without fine particles being forced out through the joint, inasmuch as the inlet chute projects far into 30 the mill and the material fed is at once engaged by the conveyer blades. The worn out

charging chute may easily be replaced at low cost, without the feed hopper being affected at all.

The drawing affixed hereto illustrates an 35 embodiment of my invention.

The inlet hopper *a* serves for introducing of material into the mill *b*, which, as it is well known, is provided with a hub or collar *c*, provided with spiral blades *d*, for conveying 40 the material. For a smooth guidance of the material there is provided within the hopper *e* and a separate sheet iron lining or chute *f* which can be easily replaced and projects with its lower end *g* far into the hub or 45 collar *c* of the mill *b*. The material introduced is at once engaged by the blades *d* and conveyed into the mill. When the chute is worn out it can be replaced without difficulty and at small expense without affecting the 50 hopper.

I claim:

In combination with a drum mill, a feed hopper merging into a feeding chute for the material introduced into said feed hopper, an 55 easily exchangeable lining in said feeding chute, said lining projecting far enough into said mill to prevent material from falling into the joint between the mill and said feed hopper.

KÄRL FAHLAND.
